UNITED STATES PATENT OFFICE.

WILLIAM H. TRAPHAGEN, OF ROCKFORD, ILLINOIS, ASSIGNOR TO THE
EMERSON MANUFACTURING COMPANY, OF SAME PLACE.

CULTIVATOR.

SPECIFICATION forming part of Letters Patent No. 629,727, dated July 25, 1899.

Application filed March 11, 1896. Serial No. 582,762. (No model.)

To all whom it may concern:

Be it known that I, WILLIAM H. TRAPHAGEN, a citizen of the United States, residing at Rockford, in the county of Winnebago and State of Illinois, have invented certain new and useful Improvements in Cultivators, of which the following is a specification.

The object of this invention is to form an attachment between the shovels and drag-bar of a cultivator so that the shovels can be arranged in what is known as "open order" and "echelon."

In the accompanying drawings, Figure 1 is an isometrical representation of a cultivator drag-bar and the shovels arranged in open order. Fig. 2 is a similar representation showing the shovels arranged in echelon. Fig. 3 is an enlarged representation of one of the brace-bars and a portion of the drag-bar. Fig. 4 is an isometrical representation of the shovel-standard bracket. Fig. 5 is an isometrical representation of the cap strengthening the shovel-standard against lateral strain. Fig. 6 is an isometrical representation of the upper portion of the shovel-standard.

The drag-bar represented in the drawings consists of two parallel bars 1, held separated by tubular blocks 2, having their front ends converging and connected to a yoke 3, forming a part of the coupling between the drag-bar and main frame of the cultivator. To the outer faces of the bars 1 are located brace-bars, bent to form parallel portions 4 and a diagonal portion 5. Each of the parallel portions is provided with a transverse opening 6. A bolt 7 passes through the drag-bar, tubular blocks, and the horizontal portions of the brace-bars lying in contact with the outer faces of the parallel bars of the drag-bar. A bolt 8 connects the horizontal portion of the brace-bar with the drag-bar. A bushing 9 is located upon the bolt and serves to support that end of the brace-bar and hold it the required distance from the drag-bar.

Upon the outer face of each horizontal portion of the brace-bar is located a bracket 10, having a central perforation 11 to receive its bolt and has flanges embracing the upper and lower edges of the brace-bar and has vertical ribs 12. Between these vertical ribs is lo-

cated a shovel-standard 13, of rectangular bar form and having an opening to receive the bolt. A cap 14 is placed upon the bolt and has vertical ribs embracing the vertical edges of the shovel-standard, and a nut placed upon the bolt serves to clamp the shovel-standard and the drag-bar together. By means of the brace-bars the location of the shovel-standard can be changed to set the standards nearer or farther from the drag-bar by reversing the brace-bar end for end, transferring the bolts and bushings to correspond, and when the second shovel from the forward end of the drag-bar is farther from the drag-bar than the first shovel their position is said to be "open order," as shown at Fig. 1, and when set as shown at Fig. 2 they are said to be in "echelon."

It will be noticed that the attachments of all the shovel-standards are the same, with the exception of the third standard from the front, it being located on the outside of the drag-bar. The cap of this standard has a central depression of a size to receive the head of the bolt connecting it with the drag-bar, and the outer edges of this cap are rounded. The location of this standard with respect to the carrying-wheels of the cultivator is such that in swinging the drag-bar during the process of cultivation the attachment of the standard with the drag-bar will engage the wheel and some part of the structure be broken, but by making the cap smooth and allowing the countersinking of the holding-bolt this objection is removed. This cap can be used on all the standards without detracting from the merits of the invention.

The handle 15 takes the place of the tubular block of the rear standard, and a brace-rod 16 holds it at the proper angle.

The shovels 17 have a connection with their standards in any suitable manner.

I claim as my invention—

1. In a cultivator the combination of a drag-bar, two shovel-standards, a brace-bar connecting the standards having two parallel portions and a diagonal portion, the parallel portions connected with the standards in order that it may be made changeable end for end.

2. In a cultivator the combination of a drag-bar, shovel-standards secured thereto by means of a bracket, a cap and a retaining-bolt, the cap of one of the standards on the outside of the drag-bar having a curved and smooth outline and having a recess for the reception of the head of the retaining-bolt in

order that the cap or head of the bolt will not engage the wheel.

WILLIAM H. TRAPHAGEN.
